UNITED STATES PATENT OFFICE.

PATRICK J. DUFFY, OF HOLYOKE, MASSACHUSETTS.

GAUGE AND SUPPORT.

Application filed January 12, 1923. Serial No. 612,857.

To all whom it may concern:

Be it known that I, PATRICK J. DUFFY, a citizen of the United States, residing at Holyoke, in the county of Hampden and 5 State of Massachusetts, have invented certain new and useful Improvements in Gauges and Supports, of which the following is a specification:

The present invention relates particularly 10 to means for properly gaging and temporarily supporting the cross-pieces in buildings on which wall electric switch boxes and the like are mounted.

The object is to provide an implement of 15 this kind that can be quickly positioned and will constitute an accurate gauge and support for such cross-pieces.

In the accompanying drawings:—

Figure 1 is a view in elevation showing 20 the device in position,

Figure 2 is a perspective view of the device,

Figure 3 is a sectional view therethrough.

As disclosed in said drawings, spaced wall 25 studs are indicated at 6, and between these studs are placed supporting bars 7, between which the usual boxes for electric wall switches or other instrumentalities are mounted. These boxes are ordinarily of a 30 standard size, and are placed at a predetermined distance above the floor. The present instrument is particularly intended for positioning said cross bars 7.

The implement comprises a body, which is 35 composed of angularly disposed walls 8 and 9 adapted to engage the angular faces of the studs 6. The free edge of one of the walls, as 8, is provided with an indicator, in the form of a pointer 10, preferably 40 placed midway between the top and bottom edges of said wall. Said wall is furthermore provided with an integral tubular extension 11, in which is mounted a reciprocatory plunger 12 having a reduced terminal 13 at its inner end, constituting a spur 45 that is adapted to be driven into the face of the studs. The plunger is held against detachment by a pin 14 engaged in a slot 15 formed in the extension 13, said slot permitting a limited movement of the plunger. Said plunger is also preferably provided 50 with a buffer 16 that acts as a cushion if the plunger is driven the full limit of its inward movement. The outer projecting end 55 of said plunger is provided in one side with a socket 17, and alongside the extension 11,

is a fulcrum projection 18 arranged on the side of the plunger containing the socket 17.

The other wall 9 of the implement is slightly shorter than the wall 8, and has 60 offset flanges 19, forming oppositely disposed seats provided with outer stop walls 20 formed by the ends of the wall 8. Filler blocks 21 may be employed on said seats, being detachably held in place by screws 22. 65 The said wall 9 also is provided on its inner side with a spur 23, which is in line with the spur 13 and with the indicating pointer 10.

The operation of the device is substantially as follows: The height of the center 70 of the box to be mounted on the wall is measured on the two adjacent studs 6 and marked by a pencil, as indicated at 24. The implement is then placed with the wall 8 against the outer face of one of the studs, and with the pointer 10 aligned with the line 24. The wall 9 is against the inner 75 side face of the stud and the spur 23 is embedded in said face. The plunger 12 is then struck with the hammer and its spur 80 13 embedded in the outer face of the studs.

As a consequence the implement will be temporarily but effectively mounted on the stud and the upper and lower seats 19 will be located equidistant from the line 24. The 85 cross pieces 7 can thus be positioned against said seats and the space between will be the space to be occupied by the box. The distance between the two seats 19 is of course 90 the standard height of the box, but if a longer box is employed the filler blocks 21 are utilized. It will be understood that two of these implements are simultaneously used, one on each stud, it only being necessary to 95 reverse them. To release said implement it is only necessary for the operator to take a screw-driver, insert the end in the socket 17 of the plunger 12, and by employing the projection 18 as a fulcrum, the plunger can be 100 withdrawn. The placing of the spurs 13 and 23 in line with the indicator pointer 10 is important, inasmuch as it permits the proper positioning of the device, and the driving of the plunger will not cause the implement to wobble and become displaced. 105

From the foregoing, it is thought that the construction, operation and many advantages of the herein described invention will be apparent to those skilled in the art, without further description, and it will be understood that various changes in the size, shape, proportion and minor details of con-

struction may be resorted to without departing from the spirit or sacrificing any of the advantages of the invention.

Having thus fully described my invention, what I claim as new, and desire to secure by Letters Patent, is:—

1. In a gauge of the character set forth, a body comprising angularly disposed plates adapted to engage different faces of a wall 10 stud or the like, means for supporting the gauge and work on said wall stud or the like, comprising devices on both of said plates for embedment in the stud faces, and a work support on said body.
- 15 2. In a gauge of the character set forth, a body comprising angularly disposed plates adapted to engage different faces of a wall stud or the like, a plunger in one plate having a spur for embedment in the 20 stud, means on the other plate coacting with the spur to support the body on said wall stud or the like and a work support on said body.
- 25 3. In a gauge of the character set forth, a body comprising angularly disposed plates adapted to engage different faces of a plate stud or the like, a plunger in one plate having a spur for embedment in the stud, and a work support on the other plate of said body.
- 30 4. In a gauge of the character set forth, a body comprising angularly disposed plates adapted to engage different faces of a wall stud or the like, a plunger in one 35 plate having a spur for embedment in the stud, and also provided with a tool-receiving socket, and a fulcrum for a tool engaged in said socket, said fulcrum being located alongside the plunger.

5. A gauge of the character set forth, 40 comprising a reversible body having oppositely arranged work supporting seats at its ends, and means for securing the body to a support with either seat uppermost and both simultaneously exposed to be engaged by 45 and to position pieces of work.

6. A gauge of the character set forth, 45 comprising a body having angularly disposed walls, a support-engaging spur projecting from one wall, a second support-engaging spur on the other wall and coacting with the first spur to sustain the body 50 on a support, and a work holding seat on said body.

7. A gauge of the character set forth, 55 comprising a body having angularly disposed walls, a support-engaging spur projecting from one wall, a second support-engaging spur on the other wall said spurs 60 cooperating to sustain the body in any desired position on a support, and a work holding seat on the first mentioned wall of said body.

8. A gauge of the character set forth, 65 comprising a body having angularly disposed walls, one of said walls having oppositely disposed work-supporting seats at its ends, and said wall having a fixed support-engaging spur, a plunger slidably mounted in the other wall and having a spur in registry with the first spur, an indicator on said latter wall in registry with the spurs, and means whereby the plunger may be operated to extract the plunger spur from a support. 75

In testimony whereof, I affix my signature.

PATRICK J. DUFFY.
